Machinery Corporation, Paterson, N. J., a
corporation of New Jersey

Application June 20, 1930, Serial No. 462,517,
and in Great Britain July 16, 1929

30 Claims. (Cl. 1—32)

This invention relates to heel-attaching machines and is particularly, but by no means exclusively, concerned with machines for securing wooden Louis or like heels to shoes.

5 When attaching Louis or similar heels of wood to shoes, it is desirable, for the purpose of obtaining a close fit at the crease between the heel and heel-seat of the shoe, that the nails or other attaching fastenings which are driven from the 10 inside of the shoe shall be positioned as closely as possible to the edge of the heel without emerging from the peripheral portion thereof. When thus driving nails close to the edge of a Louis heel, there is, however, the danger that the nails 15 may split the heel already strained by the pressure exerted in forcing the heel against the heel-seat for the attaching operation. It is one of the several objects of the present invention to provide for so clamping together, in a heel-attaching 20 machine, a shoe and a heel to be attached thereto and for so inserting the attaching nails that the latter may be driven through the heel-seat and into the heel close to the crease without 25 damage by such effects as the attaching nails protruding through the side walls of the heel, or the splitting of said heel.

The invention comprises, as one of its several features whereby the above object is attained, a shoe-entering element or support, shown as a 30 jack utilized for attaching heels by nailing from within the shoe, a co-operating pressure device or head, a plurality of heel-contact or pressure members carried by and bodily movable upon the head independently thereof, and actuating connections between the members, which connections are constructed and arranged to permit simultaneous bodily movement of the members in the head, preferably independently of one another. In the present embodiment of the invention, the contact members are in pairs, one pair being thus movable independently of another. Herein the connections appear as including a compensating lever joining one pair of the contact members, said lever floating or being 40 fulcrumed upon levers connecting to another pair. We prefer to employ, and this regardless of the manner of connection, contact or pressure members at the tread-face of the heel to be attached and at the rear and opposite sides of its peripheral surface. Generally, the effect of our improved pressure means is to produce automatic accommodation of the contact members to heels of different shapes, and thus firm, uniform 45 pressure upon the work. One of the contact members, which may be at the side of the heel to be attached, may be carried by a bar movable in curved guideways in the pressure-head. As illustrated, opposite members are thus mounted, and 50 are joined by actuating levers to the compensating lever which connects the companion members.

We preferably associate with the pressure-head a contact member, as that for the heel-breast, carried by a lever fulcrumed upon the frame, this lever being moved by connections to the pressure-head. In the present instance, the actuating 65 connections are through both this primary carrier-lever and a secondary lever fulcrumed upon the primary lever, and upon which the contact member is mounted. Initial actuation of one lever brings the member into proximity to the heel in substantially the correct vertical relation, while the movement of the other thereafter produces the final clamping engagement. To avoid defacing the work, one of the heel-contact members, as that at the rear, may be free to rock upon the carrier and also to slide thereon in the direction of inclination of the surface with which it contacts under the influence of the pressure applied to the work.

As another feature of the invention, the support for the shoe has a fastening-receiving passage inclined with respect to its longitudinal axis, in which passage is movable a rigid driver, in combination with a driver-actuator, which may be furnished by a plunger movable axially of the support, the driver and actuator being provided with a connecting projection and depression. The support has plural passages, with each of which are associated, in the actuator, outwardly extending ways, respectively receiving the projections from the drivers. There is thus furnished a simple, durable organization, by which the heel-attaching nails may be inserted in an inwardly inclined relation at points in proximity to the crease without risk of their breaking through the peripheral wall of the heel. To avoid interference of the sides of the support with the work, each driver is offset outwardly from the bar by which it is carried, the driver and bar being movable in different portions of an inclined 85 90 95 100 105 110 115 120 passage in the shoe-support.

In the accompanying drawings,

Fig. 1 is a broken side elevation of one preferred form of shoe-supporting and heel-clamping mechanism according to the invention, with a shoe and heel in clamped position;

Fig. 2 is a front elevation, with a part removed, of the heel-clamping mechanism illustrated in Fig. 1 and shown on a larger scale;

Fig. 3 is an enlarged side elevation, partly in section, of the heel-clamping mechanism shown in Fig. 1;

Fig. 4 is a plan view of part of the heel-clamping mechanism shown in the above figures;

Fig. 5 is an enlarged section on the line V—V in Fig. 3;

Fig. 6 is a section on the line VI—VI in Fig. 5;

Fig. 7 is a central, vertical section of the shoe-supporting mechanism shown in Fig. 1 but on an enlarged scale;

Fig. 8 is a front elevation of the shoe-support of Fig. 7;

Fig. 9 is a plan view of the shoe-support with a top plate thereof removed; and

Fig. 10 is a plan view of the top of the shoe-support.

The form of our improved mechanism herein disclosed, which will be considered as being applied to a machine such as is shown, for example, in the specification of British Letters Patent No. 23,031 of 1911, comprises two work-engaging members, one above the other, between which the work is clamped. The lower, work-supporting member (see Figs. 1 and 7 to 10), which enters the heel-end of a shoe to be operated upon and from which the nails are driven through the heel-seat of said shoe into the heel, comprises a base 1 fixed in the frame of the machine. The base has in it a vertically slideable plunger 2, which is raised to drive the nails. The plunger at its upper end carries a plate 3 having in its top face undercut depressions 4 to receive the lower ends of driver-bars 5, 6, 6 and 7, 7. The driver-bars are slidably mounted in a block 8 fixed on the base 1. This block 8 is tapered upwardly, having roughly the form of a truncated cone of say 50° angle when viewed from the side, and has fixed to it a block 9, in which are passages for the driver-bars and drivers 109 fixed to the upper ends of the bars. The block 9 has fixed to its upper face a plate 10 against which the inside of the heel-end of a shoe is pressed, as will hereinafter appear, said plate having formed in it nail-receiving driver-holes 11. The plate 10 and the block 9 are shaped to enter and more or less snugly fit within the heel-end of a shoe, but are of such a size and the holes in the plate are so arranged that they may be used for operating upon a reasonable variety of sizes of shoes. The lower face of the block 9 and the upper face formed on the roughly conical lower block 8 by the truncation of the latter are of the same shape and area and coincident when the blocks are secured together. The driver-holes in the plate are shown as so arranged that two nails are driven close together near the back of the heel and two at each side of the heel. All the driver-bars are inclined upwardly and inwardly toward the longitudinal axis of the support. The two drivers at the rear of the heel-block are connected to the single driver-bar 5. The four drivers nearest the rear of the heel-block are all of such a character and so connected with their driver-bars 5 and 6, 6 as to enable the nail-passages to emerge from the upper surface of the plate 10 close to its margin, and therefore to cause the nails to enter the heel close to the rand-crease. The drivers are relatively short and formed on plates, one of which is shown at 12 in Fig. 7, which can be so secured to the ends of the driver-bars that the driver moves in a path parallel to that of the bar but offset outwardly from the driver-bar-path. The length of the driver and the amount of offset are such that the bottom end of the driver, when in its lowered position, lies inside the shoe, and the driver-path, if extended downwardly, would emerge from said block 9 and intersect the inside of the counter-portion of the shoe or only just clear it. In other words, the length and inclination of the driver and its relation to its bar are such that it reciprocates substantially within the counter-portion of the shoe, enabling a nail to be driven into the heel-seat inclined upwardly and inwardly and quite close to its edge.

The undercut depressions 4 receiving the bars are, in each case, perpendicular to the driver-path. There is thus established a push-and-pull connection between these members allowing the lateral movement of the lower ends of the driver-bars necessitated by the inclination of the driver-paths to the plunger-path.

A gage 14 to position the shoe lengthwise on the plate 10 is mounted in guideways formed at the top of the block 9 beneath the plate 10. The gage may be adjusted forwardly or rearwardly in the guideways by a screw 15 rotatably mounted in the gage and threaded into the block.

It is desirable, in view of the considerable inclination to the heel-seat at which the nails are driven, to guard against evil results from the tendency of the nail-head and driver-end to slide relatively transversely of the driving path during the driving stroke and to give as smooth a heel-seat as possible, by employing nails with rounded heads received in complementary depressions 115 in the drivers. The preferred form of nail is of usual character as to the dimensions of its shank and the nature of the point, though preferably the nail is made from wire threaded with a multiple thread of coarse pitch, so as to be in effect a screw-nail, but the face of its head adjacent the shank is plane and perpendicular to the axis thereof, and its other face is convex, the head being a plane section of a sphere considerably less than a hemisphere.

The clamping mechanism for the heel (Figs. 1 to 6) comprises a heel-tread-face-engaging member 16, a member 17 engaging the rear face of the heel near its heel-seat end, members 18, 18 engaging the opposite sides of the peripheral wall of the heel close to its seat-end and well toward the front, and a member 19 engaging the curved portion of the breast of the heel near the seat-end. The tread-face-engaging member 16 consists of a plate 20 carried by a block 21 and adjustable on the block about a horizontal axis extending across the heel on the face of the plate. The block 21 is slidably mounted in the lower end of a carrier 22 so as to be adjustable horizontally rearwardly and forwardly of the heel. The tread-face-engaging plate 20 may therefore be adjusted angularly to suit the angle of the tread-face of the heel in relation to its seat-face, and longitudinally of the shoe to suit the style of the heel. The carrier 22 has, extending upwardly from it, a stem 23 threaded into the enlarged lower end 24 of a rod 25 which is slidable in a vertical bearing in a vertical plunger 26, which carries the heel-pressure device or head. The rod is urged downwardly by a spring (not shown) and has fixed to its upper end a hand-wheel 27 (Fig. 1), by which it may be rotated to adjust the tread-plate 20 vertically. The tread-plate 20 is maintained against rotation by a vertical groove formed in an extension 28 of the carrier 22, which groove receives a tongue on a housing 29 mounted at the lower end of the plunger 26 and furnishing the body of the pressure-head. The wheel 27 is held against the top of the plunger 26 by the spring while the vertical adjustment of the plate 20 is made.

The member 17 which engages the rear face of the heel comprises a leather or like pad 128 secured to a plate 129 guided upon a carrier-block 30 to slide freely thereon in a direction fore-and-aft of the heel, there being a pin 31 fixed in the plate 129 and entering a recess in the block 30, which limits the downward movement of the plate 129 along its guides. The block 30 is free

to turn about a horizontal axis extending transversely of its guideway on a member 32, which is slidingly mounted in a guideway formed in the enlarged lower end 33 of a vertical spindle 34 and 5 adjustable forwardly and rearwardly of the heel in the guideway by a screw 35. The spindle 34 is vertically slidable in the housing 29. A spring 36 in a bore in the spindle 34 engages at its lower end a pin 37, fixed in the housing and passing 10 through a vertical slot 38 in the spindle, and at its upper end engages a screw 39 threaded into the spindle-bore. This spring is of sufficient strength to just raise the spindle and the parts carried thereby. A substantially horizontal compensating lever 40 has one end resting on the upper end of the enlarged portion 24 of the tread-face-plate-adjusting-rod 25, and the other end upon the upper end of the spindle 34. Washers 15 41 and 42, having convex lower surfaces, are interposed between the lever 40 and the spindle 34 and portion 24, respectively. The convex surfaces of the washers are seated in concave recesses in the head of the screw 39 and in the portion 24.

20 The members 18, 18 which engage the side faces of the heel are similar at each side, and each comprises a leather pad 43 fixed to a small block 44, which is connected by a short upwardly inclined link 45 to the lower end of a curved bar 46. The pivots joining the link 45 to the block 44 and bar 46 extend horizontally fore-and-aft of the heel. Each link 45 is normally pressed down about its pivotal connection to the bar by a spring 47 carried by said bar, and its downward movement is limited by a stop-projection 48 on the bar. Each bar 46 is curved and guided to move about a horizontal axis extending forwardly and rearwardly of the heel. This axis may be about two and a half inches from the fore-and-aft vertical mid-plane of the heel on the side opposite the bar, and some four inches above the seat-face of the heel when clamped, so as the bar is moved downwardly about that axis, its lower end moves inwardly toward the heel. The bars 46 travel in curved guideways formed in the housing 29, and are normally urged upwardly by springs 49 attached to the bars and to the housing. The bars have on their outer faces rack-teeth 50 which mesh with gears 51 fixed on horizontal shafts 52 extending forwardly and rearwardly of the heel and rotatably mounted in the housing. Each shaft 52 has fixed to it a pinion 53 which meshes with a gear-segment 54 formed on one arm of a lever 55 pivoted on a shaft 56 mounted in the housing 29. The inner ends of the levers 55 have formed on them balls 57, which enter a bore in the compensating lever 40 to provide a floating fulcrum therefor. The curved contact-faces of the washers 42, 41 and the tread-plate-adjusting-rod 25 and the head of the screw 39 and the ball-connections between the levers 55 and 40 permit the compensating lever 40 not only to rock longitudinally about the ball-ends 57, bringing the members 16 and 17 successively 60 into contact with the tread-face and rear of the heel, but to rock laterally as well to allow the members 18 to press equally against the sides of the heel without displacing it. When the clamping mechanism which engages the heel is in its raised, inoperative position, the hand-wheel 27 on the tread-face-plate-adjusting-rod 25 is held by its spring in engagement with the top of the plunger 26, and the springs 49, which act upon the curved bars, raise these bars and, through 65 the racks 50, gears 51, pinions 53 and levers 55, hold a shoulder 58 on the head of the screw 39 down upon a seat 59 on the housing 29.

70 The heel-breast-engaging member 19 is formed at the lower end of a screw 60 adjustably mounted in an end section 61 pivoted at 62 to a lever 63. The portion 61 has a toothed segment 64 engaged by a screw 65, rotatably mounted in the lever 63 and having on it a knurled hand-piece, by which it may be rotated to adjust the section 61 and heel-breast-engaging member 19 about the pivot 62. The lever 63 is fulcrumed at 66 to a primary lever 67, which is pivoted at 68 to the frame of the machine. A spring 69, connected between the secondary lever 63 and primary lever 67, tends to swing the member 19 away from the heel about the fulcrum 66. The plunger 26 has fixed to its upper end a collar 70, which has projecting from it a pin 71 entering a slot 72 in a bar 73 pivotally connected at its lower end to the lever 67. A spring 74 surrounds the bar 73, said bar having in it a screw 75, which is engaged by the pin 71 to lift the lever 67 and therefore the member 19. The lever 63 has at its upper end a bearing 76 for a spring-plunger 77, the force of the spring being adjustable by a screw 78. Outward movement of the plunger from the bearing 76 by the spring is limited by the engagement of a collar 79 on the plunger with a shoulder in the bore of the bearing. The plunger engages a cam-groove 80 formed on the collar 70. A screw 81 in the lever 67 engages a lug 82 on the machine-frame to limit downward movement of said lever.

80 When a shoe S and a heel H to be attached thereto have been placed upon the lower clamping member 10, the tread-face-plate 20 is adjusted by the hand-wheel 27, so that, when the upper clamping mechanism is lowered, the tread-face-plate will engage the heel just before the rear engaging member 17 and the breast-engaging member 19. When the plunger 26 of the 85 machine and with it the housing 29 are first lowered by a treadle, as described in the aforementioned specification, the plate 20 first contacts with the heel, and as the plunger 26 continues to be lowered, the spring associated with the rod 25 yields and the members 17 and 19 contact with the heel practically simultaneously. During this part of the movement of the plunger 26, the lever 67 is pushed down by the pin 71 through the spring 74 until the screw 81 engages 90 the lug 82. The position of the member 19 vertically along the heel may be adjusted by means of the screw 81. After the tread-face-engaging plate 20 and rear and breast-engaging members 17 and 19 have in this way all contacted with the heel, they remain stationary or substantially so both relatively and absolutely during further downward movement of the plunger 26 and housing 29, and the compensating lever 40 therefore 95 also remains stationary. During such further downward movement of the plunger 26 and housing 29, still by means of the treadle, the pivots 56 of the levers 55 on the housing 29 are carried down, and, since the inner ends 57 of the levers 55 rest in the bore in the now stationary compensating lever, the levers 55 are rocked on their pivots 56 and move the clamping members 18 into engagement with the sides of the heel. At this time, the lever 40 rocks laterally upon its curved supports furnished by the members 24 and 39, as far as is necessary to act as a compensator, and permits independent movement of the pairs of heel-contact members 16, 17 and 18, 100 105 110 115 120 125 130 135 140 145 150 155 160 165 170 175 180 185 190 195 200 205 210 215 220 225 230 235 240 245 250 255 260 265 270 275 280 285 290 295 300 and the cam-groove 80 and plunger 77 so move relatively that the spring of the plunger 77 is compressed and yieldably forces the member 19 against the breast of the heel, through the oscillation of the lever 63 about the pivot 66. The movement of the side clamping members into engagement with the heel is partly in the direction of movement of the plunger 26 and housing 29, and partly along the arcuate guideways in the housing. In the condition of the parts now attained, all the heel-engaging members are practically locked in contact with the heel against movement from it. When power is next applied to the machine, the plunger 26 and housing 29 are moved slightly down to more firmly clamp the heel against the shoe, compressing the heel-seat. The inclination of the heel-engaging surfaces of the side members 18 and of their links 45 is such that any tendency of the heel to compress or of the heel-clamping mechanism to spring, or, as the result of increasing compression of the work-engaging pad faces, of the parts of the mechanism to move, results in increased inward pressure of the side members on the heel, owing to a straightening virtual toggle composed of the two inclined links 45 held against outward movement at their outer ends by the bars 46, and urged against the heel-engaging members and the interposed heel at their inner ends. This results also in increased pressure being applied through the breast-engaging member 19 by reason of the relative movement between the cam-groove 80 and the plunger 77 acting to further compress the spring of said plunger. The heel is thus not only held against the upward nail-driving thrust at its tread and at the four points round its front, back and sides near its relatively frail and easily split heel-seat-margin, but is actually subjected to a widthwise compression during the nailing, tending to increase as said thrust is applied and to definitely counteract any splitting tendency. During such final settling down of the clamping mechanism under the heavy power-pressure applied by the plunger 26, any further descent of the rear member 17 results only in a sliding movement downward between the pad 128 and block 30 by reason of the tongue-and-groove connection between them without moving the pad, which will be held by its engagement with the heel. Thus, marking of the rear face of the heel by a movement of the pad over it will be prevented. The heel is during the nailing held very solidly at five points. Even if the material of the heel or the mechanism operated by the plunger yields in some way during the nailing, not only do the side members, as indicated above, increase their inward gripping and compressing thrust, but the rear pad is wedged harder against the heel along its tongue-and-groove connection with its actuating mechanism, and extra lateral compression on the heel is for that reason applied.

Having described our invention, what we claim as new and desire to secure by Letters Patent of the United States is:

1. In a heel-attaching machine, a shoe-support, a pressure-head co-operating therewith, plural heel-contact members guided in the pressure-head for bodily movement, and actuating connections between the members arranged to move them simultaneously in the head, said connections being constructed and arranged to permit movement of the members in the head independently of one another.

2. In a heel-attaching machine, a shoe-support, a pressure-head co-operating therewith, pairs of heel-contact members movable upon the head, and actuating connections between the members, said connections being constructed and arranged to permit the movement of one pair independently of another.

3. In a heel-attaching machine, a shoe-support, a pressure-head co-operating therewith, a pair of heel-contact members movable upon the head, a lever connecting the members, a third heel-contact member carried by the head, and actuating connections to said third member furnishing a fulcrum for the lever.

4. In a heel-attaching machine, a shoe-support, a pressure-head co-operating therewith, a pair of heel-contact members movable upon the head, a lever connecting the members, a third heel-contact member carried by the head, and a lever connected to the third contact member and upon which the first-mentioned lever is fulcrumed.

5. In a heel-attaching machine, a shoe-support, a pressure-head co-operating therewith, a pair of heel-contact members movable upon the head, a lever connecting the members, a second pair of heel-contact members movable upon the head, and a lever connected to each of said second pair of members and fulcrumed upon the head, the levers of this second pair of members furnishing a fulcrum for the first-mentioned lever.

6. In a heel-attaching machine, a shoe-support, and a heel-pressure device co-operating with the support and comprising a tread-pressure member and rear, side and breast-pressure members, said members being arranged for movement independently of one another toward and from a heel on the support.

7. In a heel-attaching machine, a shoe-support, a heel-pressure device co-operating with the support and comprising rear and breast-pressure members, connections between said members arranged to cause one to move the other, side pressure members, and actuating connections between said side pressure members and the connections for the rear and breast members.

8. In a heel-attaching machine, a shoe-support, a heel-pressure device co-operating with the support and comprising a tread-pressure member and rear, side and breast-pressure members, means for moving the device and support relatively to cause engagement between the heel and the tread-pressure member, and connections arranged to produce successive contact with the heel of the rear and breast-pressure members and the side pressure members.

9. In a heel-attaching machine, a shoe-support, a pressure device co-operating with the support and comprising spaced heel-pressure members, and a lever connecting the members and fulcrumed to rock both longitudinally and laterally.

10. In a heel-attaching machine, a shoe-support, a pressure-device co-operating with the support and comprising spaced heel-pressure members, and a lever connecting the members, said lever having a floating fulcrum.

11. In a heel-attaching machine, a shoe-support, a pressure device co-operating with the support and comprising spaced heel-pressure members, a lever connecting the members, another heel-pressure member, and connections to said other member furnishing a fulcrum for the lever.

12. In a heel-attaching machine, a shoe-support, a pressure device co-operating with the support and comprising spaced heel-pressure members, a lever connecting the members, intermediate heel-pressure members, and a lever connected to each intermediate member, said levers supporting the first-mentioned lever. 80
13. In a heel-attaching machine, a frame, a shoe-support mounted thereon, a pressure device movable upon the frame and co-operating with the support, a lever fulcrumed upon the frame, a second lever fulcrumed upon the first, a heel-contact member carried by the second lever, and connections to the pressure device for moving the levers. 85
14. In a heel-attaching machine, a frame, a shoe-support mounted thereon, a pressure device movable upon the frame and co-operating with the support, a lever fulcrumed upon the frame, a heel-contact member carried by the lever, and a plurality of connections to the pressure device arranged to impart independent movements to the contact member. 90
15. In a heel-attaching machine, a shoe-support, a pressure device movable toward and from the support, a primary lever fulcrumed adjacent to the pressure device, a secondary lever fulcrumed upon the primary lever, a heel-breast-contact member carried by the secondary lever, and means for actuating the levers. 95
16. In a heel-attaching machine, a shoe-support, a pressure device movable toward and from the support, a primary lever fulcrumed adjacent to the pressure device, a secondary lever fulcrumed upon the primary lever, a heel-breast-contact member carried by the secondary lever, and connections to the pressure device for actuating both of the levers. 100
17. In a heel-attaching machine, a shoe-support, a pressure device movable toward and from the support, a primary lever fulcrumed adjacent to the pressure device, a secondary lever fulcrumed upon the primary lever, a heel-contact member carried by the secondary lever, and a yieldable connection between the pressure member and each lever. 105
18. In a heel-attaching machine, a shoe-support, a pressure device movable toward and from the support, a primary lever fulcrumed adjacent to the pressure device, a secondary lever fulcrumed upon the primary lever, a heel-contact member carried by the secondary lever, means arranged to actuate one lever, a stop for said lever, and means for actuating the other lever after the stop has become effective. 110
19. In a heel-attaching machine, a shoe-support, a lever co-operating with the support and having a pivoted section, means arranged to vary the angle of the section, and a heel-contact member variable in position upon the section. 115
20. In a heel-attaching machine, a shoe-support, a pressure-head co-operating therewith and provided with opposite curved ways, and heel-contact members guided by said ways and arranged for engagement with opposite sides of a heel to be attached. 120
21. In a heel-attaching machine, a shoe-support, a pressure-head co-operating therewith and provided with a curved guideway, a curved bar movable in the way, and a heel-contact member carried by the bar. 125
22. In a heel-attaching machine, a shoe-support, a pressure-head co-operating therewith and provided with a curved guideway, a curved bar movable in the way, a heel-contact member carried by the bar, and a link interposed between the bar and contact member. 130
23. In a heel-attaching machine, a shoe-support, a pressure-head co-operating therewith and provided with opposite curved guideways, a curved bar movable in each way, a heel-contact member carried by each bar, a lever joined to each bar, and a unitary actuating member joining the levers. 135
24. In a heel-attaching machine, a shoe-support, a pressure-head co-operating therewith and provided with opposite curved guideways, a curved bar movable in each way, a heel-contact member carried by each bar, a lever joined to each bar, a compensating lever fulcrumed upon both bar-levers, and a heel-contact member connected to the compensating lever. 140
25. In a heel-attaching machine, a support for a shoe and for a heel having an inclined rear portion, and a pressure device movable into and out of co-operation with the support and comprising a carrier and a rear heel-contact member free to rock upon the carrier to conform to the inclination of the rear portion of the heel and to slide on the carrier in the direction of inclination of said rear portion. 145
26. In a heel-attaching machine, a shoe-support, and a pressure device movable into and out of co-operation with the support and comprising a carrier, a block adjustable upon the carrier and a heel-contact member free to slide and rock upon the block under the influence of the pressure applied to the work. 150
27. In a heel-attaching machine, a shoe-support, actuating connections, and a pressure device movable into and out of co-operation with the support and comprising a spindle yieldable upon the actuating connections, a block adjustable upon the spindle and a heel-contact member free to slide upon the block. 155
28. In a heel-attaching machine, a shoe-support having fastening-receiving passages inclined with respect to the longitudinal axis of the support, an actuating member having a way corresponding to each passage and extending outwardly from said axis, and a driver movable in each passage and having a projection entering the corresponding way. 160
29. In a heel-attaching machine, a shoe-support having a passage inclined with respect to the longitudinal axis of the support, a driver-bar movable in one portion of the passage, a driver attached to and offset outwardly from the bar and movable in another portion of the passage, and an actuator for the driver-bar movable axially of the support. 165
30. In a heel-attaching machine, a jack provided with passages inclined upwardly and inwardly, a plunger moving axially of the jack and having at its upper extremity an enlargement, there being ways formed in the enlargement and radiating from the axis of the jack, and drivers movable in the jack-passages and having portions entering the plunger-ways. 170
